SUN SHIELD

Frank J. Simon, Hannibal, Mo.

Application April 3, 1946, Serial No. 659,393

1 Claim. (Cl. 224—5.1)

1

This invention relates to sun shields of the type to be worn on the body, the primary object of the invention being to provide a support for the sun shade in the form of a harness which may be readily and easily positioned over the shoulders of the wearer, the harness being of a construction to firmly support the sun shade proper.

Another object of the invention is to provide a sun shade including a support which will permit the free use of both hands of the person wearing the sun shade, to the end that the sun shade may be used by workmen exposed to the sun's rays.

Still another object of the invention is to provide a sun shade including a support having means whereby the sun shade may be adjusted to various angular positions, for the convenience of the user.

With the foregoing and other objects in view which will appear as the description proceeds, the invention consists of certain novel details of construction and combinations of parts hereinafter more fully described and pointed out in the claim, it being understood that changes may be made in the construction and arrangement of parts without departing from the spirit of the invention as claimed.

Referring to the drawing

Figure 1 is an elevational view of the sun shade illustrating the manner of positioning the shade over the shoulders of a person wearing the sun shade.

Figure 2 is a side elevational view thereof, the shade being shown in dotted lines in various adjusted positions.

Figure 3 is a fragmental plan view of the shade proper.

Figure 4 is a rear perspective view of the harness used in supporting the sun shade on the body of a person.

Referring to the drawing in detail, the harness by means of which the sun shade is supported, embodies a pair of metallic straps 5 which have their upper ends curved as at 6 to fit over the shoulders of the person wearing the sun shade.

These straps are of lengths to extend an appreciable distance over the back of the wearer, the rear ends of the straps terminating at points adjacent to the waistline at the back of the wearer, where they are provided with loops 7 to

2

accommodate the belt 8 worn by the person using the sun shade.

Cushioning members 9 are secured to the under-surfaces of the curved portions of the straps 5 for the convenience and comfort of the wearer of the sun shade.

Connecting the metallic straps 5, is an arch member formed with horizontal sections 10 connected with the straps 5 at the curved portions 10 thereof, as clearly shown by Fig. 1 of the drawing. The intermediate portion of the arch member is constructed in such a way that it will lie in spaced relation with the head of the wearer of the device.

Also connecting the horizontal sections of the arch member, is a curved brace rod 11, curved downwardly to fit over the mid-section of the back of the wearer, to hold the harness or support rigid.

The sun shade proper is indicated generally by the reference character 12 and embodies a frame comprising a ring 13 and cross-arms 14, the cross-arms being inclined upwardly from the ring 13 to the point of crossing. This frame is covered by a suitable cloth 15 so that the device will also shed water to the end that the device may be used as an umbrella, if desired.

The shade 12 is connected with the arch member, by means of the bracket 16 that embodies a lower section 17 that is secured to the arch member, and an upper member which is secured to the frame of the sun shade proper. These members of the bracket are formed with heads having ridged surfaces cooperating to prevent turning of one section of the bracket with respect to the other, after the bracket has been adjusted to the 35 desired angle.

A bolt indicated by the reference character 18 extends through the heads of this bracket and a winged nut 19 is positioned on the threaded end thereof, securing the sections of the bracket together.

From the foregoing it will be seen that due to the construction shown and described, the sun shade may be readily positioned over the shoulders of a person, and held in place by means of the 45 usual belt worn by the person.

The sun shade proper may be adjusted to various angular positions to provide the maximum shade.

What is claimed is:

50 A sun shield comprising a pair of vertical rigid

strap members having curved portions and adapted to fit over the shoulders of a person wearing the sun shield, loop members formed at the lower ends of the strap members through which a belt is extended securing the lower ends of the strap members to the body of the wearer, an arch member, the ends of the arch member being secured to the curved portions of the strap members, a rod connected at the ends of the arch member, said rod being downwardly curved to fit against the back of the person wearing the shield, and a shield member supported centrally of the arch member in spaced relation thereto.
